MEANS FOR ADAPTING A GASOLINE ENGINE
TO THE USE OF OIL AS FUELCarl Hansen and Paul Besner, Montreal, Quebec,
Canada

Application April 5, 1937, Serial No. 135,179

1. Claim. (Cl. 123—32)

This invention relates to a means for adapting a gasoline engine to the use of oil as fuel and particularly to the use of what is commonly known as fuel oil.

5 It has been previously proposed to do this and devices have been developed for this purpose. However, in most of these the attachment of the device required almost complete rebuilding of the engine so that they were not of a practical character.

10 Since the saving in fuel did not warrant the expense involved. In most cases too, the device was very complicated and heavy. These known devices have, therefore, been very expensive to make and to install and generally have not provided an easy means of changing over from the use of one fuel to the other.

It is an object of the present invention to provide an internal combustion engine which can be operated both with heavy oil and with gasoline.

20 It is a further object of the invention to provide easy and convenient means for changing over the engine from the operation with one fuel to operation with the other.

25 It is also an object of the invention to provide an arrangement whereby an engine of this type can be made from an ordinary gasoline engine and will require changes in a minimum number of parts.

30 According to the present invention, when the engine is running on gasoline, the gasoline is supplied to the cylinders through the ordinary carburetor and the gasoline supply is controlled by the usual accelerator. For oil operation nozzles are provided for each cylinder and fuel is supplied to the nozzles from a pump which is controlled from the foot accelerator. The foot accelerator is connected to a change-over device and this change-over device allows the accelerator to operate either the control means for the oil pump, or the gasoline supply control means, depending upon the position to which the change-over device has been adjusted.

35 The invention is further illustrated by reference to the accompanying drawings in which an internal combustion engine is illustrated by dotted and full lines, the full lines representing the parts which must be added, or altered, according to the invention, and the dotted lines representing the conventional and unchanged parts of the usual gasoline internal combustion engine.

40 Figure 1 is a plan view of an engine adapted according to the invention showing schematically 45 the control means and the means for changing

over the engine from the use of one fuel to the other.

Figure 2 is a side elevation of the engine according to Figure 1 and taken from the side of the engine carrying manifold.

Figure 3 is a side elevation of the side of the engine opposite that illustrated in Figure 2.

Figure 4 is a section taken on line 4—4 of Figure 2.

Figure 5 is an enlargement of the nozzle shown 10 in Figure 4 with the section extended to show a preferred form of non-return valve in the nozzle.

Figure 6 is a vertical central section of the pump-distributor illustrated in elevation in Figure 3.

Figure 7 illustrates a preferred form of a changeover means showing it in end elevation and illustrating particularly the movable member.

Figure 8 is an enlarged section taken along the 20 line 8—8 of Figure 7 and shows both the movable and stationary members with their plungers.

Figure 9 is a fragmentary enlarged plan of the changeover means illustrated in Figure 1 and shows particularly the preferred form of the 25 means for limiting the action of the movable member.

In the drawings the exhaust manifold 1 has an extension 2 situated above and extending along the engine head 3. The circuit between the exhaust manifold and the extension is completed at one end by a branch connection 4 and at the other by vertical branches 5, which extend between the horizontal portion of the extension and the exhaust manifold itself. Nozzles 6 pass 30 through these branches of the extension, the cooling chamber 7 of the engine head and the engine head proper 8. Provision is also made in the engine head for a spark plug 9 which is clearly shown in Figures 4 and 3. A pump 10 receives 40 oil through a pipe-line 11 and supplies it to the nozzles through pipe-lines 12. The intake manifold 13, which is surmounted by the usual air cleaner and gasoline carburetor, has an additional aperture for the admission of air to the 45 cylinders when the engine is operating on oil. This aperture may take the form of an extension 14 with a conventional air cleaner 15 attached to it and having a valve 16 to control the amount of air admitted. This valve is operated by means 50 of rods and levers 17 and 18 which are finally connected to the changeover device 20 by means of the oil control plunger 21.

The oil pump 10 is controlled in its operation by the U bracket 22. This is moved inwardly 55

and outwardly by the operation of a pivoted rack 23 and its pinion 24. The pinion is mounted on a rod 25 which is rotated by a rod 26, which in turn, by means of levers and rods, is likewise connected to the plunger 21 on the changeover device 20.

The pump 10 with its yoke 22 is shown in section in Figure 6. It consists essentially of radially disposed cylinders 27 with a plunger 28 operating in each of them, the said plunger being controlled by a spring 29. The cylinders have apertures 30 in their walls for the admission of oil and operation of the plungers closes the apertures and forces the oil to pass through the non-return valve 31 in the nipple 32. The nipple 33 communicates with the oil supply pipe and introduces the oil into the well 34, which in turn has apertures 35 communicating with the wells surrounding the cylinders of the pump. The operation of the plungers is controlled by the cam 36 attached to the rotary disc 37 which rotates on a shaft 38. The rotary disc is slidably mounted on its shaft by means of the bearings 39 and it rotates within a collar 40 which is attached to and moved inwardly and outwardly with the yoke 22. The disc has a toothed circumference for engagement with pinion 41 mounted on the shaft 42 which is driven from the drive shaft of the engine. Movement of the yoke inwardly or outwardly causes the plunger to be more or less depressed by the action of the cam and thus controls the amount of oil supplied to each of the engine cylinders. When the yoke 22 is pulled outwardly as far as it will go the plungers are not sufficiently depressed to supply any oil to the engine.

In the enlarged section of the nozzle 6, shown in Figure 5, there is clearly illustrated open passageways 44 in its walls which communicate freely with the extension branches 5 of the exhaust manifold. Oil enters the nozzle through the nipple 45 which contains a non-return valve similar to the one described in connection with the nipple of the pump cylinders. This non-return valve is of the usual type and comprises a seat 46, a ball 47 and a spring 48 retaining the ball on the seat and closing the valve until sufficient pressure is applied.

In operation the attachment for adapting the engine to the use of heavy oil, works as follows:—

The oil is supplied from a pump 10 to the various nozzles projecting into the cylinders of the engine. These nozzles, because of the exhaust fumes passing through the extension of the exhaust manifold and thus through the passageways in the walls of the nozzles, are sufficiently heated by the fumes so that the oil passing through the nozzle can be fired in the cylinders. The proper relation between the piston strokes of the engine and the oil injection is maintained by having the oil pump geared to and driven by a shaft which is in turn driven from the drive shaft of the engine. Movement of the cam along the shaft 38 about which it rotates varies the stroke of the plunger and thus controls the amount of oil supplied to the engine cylinders and as a result speeds up or slows down the operation of the engine. Since the yoke 22 is connected by rods and levers to the plunger 21 of the changeover mechanism 20 and since the valve 16 in the intake manifold is likewise connected to the same plunger, movement inwardly and outwardly of the yoke 22 causes the corresponding opening and closing of the valve 16. In

this manner the air supply is adjusted to correspond with the oil supply.

In Figures 1, 2, 7 and 8 there is shown a device 20 for changing over the engine from the use of one fuel to the other. Figure 8 shows the position of the device for changing over the engine from the use of the carburetor to the use of the injection system. In this position the engine is at rest and the delivery of the fuel supply pump is zero. In this position of the change-over device the throttle valve of the carburetor is open and the air throttle 16 is closed. This can be mounted in any convenient position between the engine and the control panel and is here shown attached to the fly wheel casing. The device comprises a base 49 having rigidly attached thereto a stationary member 50. This stationary member carries on its surface two projections each of which contains plungers 51 and 21 respectively. These plungers are controlled by springs 52 which tend to return the heads 53 to a position which, in relation to the inner face of the member 50, is not beyond the flush position. Supported by the stationary member and rotating within it is a rotary member 54 which also has on its outer face a similar projection carrying a plunger 55, which is likewise spring controlled and which has its head normally held flush with the inner face of the rotary member. The plunger 55 is connected by means of links to the foot pedal or accelerator 56. Mounted on the rotating member 54 and extending well beyond its circumference are two radial projections 57 and 58. Radial projection 58 is connected by means of links to the bar 59 which operates the valves 60. These valves control the flow of exhaust from the exhaust manifold to the extension branches 5 which conduct the fumes about the nozzle 6. Radial projection 57 is connected by means of a Bowden wire 40 to a hand lever control 61. A spring 62 has one end connected to the base 49 of the changeover device and the other end is connected to the rotary member. The connection of the spring to the base is made at a part exactly on the vertical centre line of the rotary member while the connection to the rotary member itself is made at a point slightly to one side of this centre line. Plunger 51 is connected to the member which, in a gasoline engine, connects the accelerator pedal to the feed-controlling device.

This changeover device operates as follows:—

As shown in Figure 2, the engine cylinders are being operated with heavy oil such as fuel oil. This means that the foot accelerator 56 is connected through its plunger 55, which is registering with the plunger 21, to the yoke 22 and that the plunger 51 is disconnected from the accelerator pedal. Since the valve 16 operates with the yoke 22, it is also connected to the foot pedal 56. When pressure is taken off the pedal 56 the springs associated with the plungers bring the plunger heads flush with the surfaces of the member to which they are attached and the movable member is free to move within the stationary member. A slight operation of the control button 61 will cause, through its Bowden wire, the rotary member to move the spring 62 slightly over the vertical centre line of the rotary member. The action of the spring will then cause the member to complete its movement.

The rotary member in moving carries with it a projection 58 which is connected to and controls the valves 60. Thus, when the engine is being changed from the use of gasoline to the use of

oil, these valves open and allow the exhaust fumes to heat the nozzles; and when the changeover is being made in the opposite direction, these valves close and the exhaust is carried away through the 5 exhaust manifold in the usual manner.

Figure 9 is a plan view of a portion of the changeover device. It shows a stationary member with a cut out portion and the rotary member with a lug 63. The lug and cut out portion 10 limit the movement of the rotary member so that when the lug is at one end of the cut out portion plunger 55 registers with plunger 21 and at the other end plunger 55 registers with plunger 51. In operating the change-over device 15 to change the engine operation from the use of gasoline to the use of oil, pressure is removed from the accelerator pedal which brings the rotor plunger, to which it is attached, flush with the surface of the rotor of the change-over device. The lever 61 on the dashboard is then operated 20 and thus, by means of the Bowden wire, throws over the rotor so that its plunger is brought into registry with the other plunger of the stator so that the accelerator is then connected by 25 means of the rotor plunger and the stator plunger to the levers controlling the operation of the fuel supply pump and the manifold air inlet valve 16. Movement of the rotor from the gasoline position to the oil position carries with it 30 the arm 58, which movement in this direction causes the opening of the heat control valves 60.

With the apparatus described above an attachment is provided for a gasoline engine which adapts it to the use of oil and at the same time 35 provides an easy means of changing over from the use of gasoline to oil and back again. An engine so adapted reduces to a great extent the

exhaust odour common in internal combustion motors.

What we claim as our invention is:—

An internal combustion engine adapted to the use of both gasoline and oil comprising a gasoline carburetor, a gasoline supply for said carburetor, means for controlling the supply of gasoline to the carburetor, an oil injection nozzle for each cylinder, a pump for supplying oil to said nozzles at intervals, means for varying, independently of the speed of the pump, the amount of oil supplied by the pump, an exhaust manifold having extensions for circulating exhaust fumes about said nozzles, an intake manifold having an air inlet, a valve for said air inlet, said valve being 5 controlled by and operating with the means for varying the amount of oil supplied by the pump, and means for changing over the engine from one fuel to the other comprising a rotor and a stator, said stator carrying two plungers one of 10 which is connected to and operates the means for controlling the gasoline supply and the other of which is connected to the means for varying the amount of oil supplied by the pump, said rotor carrying one plunger connected to manual control means and adapted to register on movement of the rotor with either of the two stator plungers, and also a member connected to and operating valves between the exhaust manifold 15 and its extensions so that when the engine is adapted for operation with fuel oil the valves are open, and means for moving the rotor and its plunger from registry with one plunger of the stator to registry with the other plunger of the stator. 20
